The evenly spaced dashed broken lines in the figures that are immediately adjacent to the shaded areas and define unshaded regions, and the dot-dash broken lines, represent the bounds of the claim. The appearance of any portion of the article between the pairs of dot-dash broken lines forms no part of the claimed design. All other evenly spaced broken lines in the figures, including the features within broken line boundaries, the broken lines on the front surface to the right and left of the speaker, and the broken lines showing the display, are directed to environment. All broken lines in the figures form no part of the claimed design.
